COMBINATION SHOWER STOOL AND
DRAIN FITTING

Benjamin N. Greene, Miami Beach, Fla.

Application July 27, 1950, Serial No. 176,133

9 Claims. (Cl. 4—185)

1

The present invention relates to bathroom fixtures and more particularly to a combination shower stool and drain fitting, an object of the invention being to make a stall or cabinet shower adaptable not only for taking an all-over shower but for foot bathing also, and to permit the bather being seated at the time.

In the accomplishment of my invention a stool supporting means is housed within the drain as an adjunct thereto, a further object being the provision of such a supporting means with a standard type of drain fitting without the necessity of in any way altering the fitting or its connections other than providing a tube receiving socket on the drain's removable cover plate.

Another object of the invention is the provision of a collapsible stool which, when not in use, may be hung in an out of the way but conveniently accessible place, as on a hook in the shower wall.

Although intended primarily as a stool for stall showers, the invention may also be used in bathtubs thus providing means whereby foot bathing is made more easy and safer, especially for elderly and infirm persons. When equipping a bathtub, or a combination tub and shower, for use with the present invention, the relative positions of the drain and faucets would be such that free manipulation of the faucets could be had by a person seated on the stool.

To these ends the invention consists of a stool and means for removably supporting it as will be fully set forth in the following description and particularly defined in the appended claims.

The drawings disclosing the invention are for the purpose of illustrating a preferred embodiment thereof, it being understood that various changes in structural details may be made without departing from the spirit of the invention.

In the drawings,

Fig. 1 shows the stool in position for use, the view being an elevation with parts of the stool and its support seen in vertical central section.

Fig. 2 shows, in side elevation, the stool as collapsed and suspended from a hook against a wall.

Fig. 3 is a sectional view on line 3—3 of Fig. 1.

Fig. 4 is a sectional view on line 4—4 of Fig. 1.

In the drawings, similar reference numerals refer to similar parts throughout the different views.

Numeral 1 indicates a surface to be drained of water, such as the floor of a shower or the bottom of a bathtub. This surface is formed with an opening 2 surrounded by a slightly depressed annular flange 3 which supports a standard type

2

of drain fixture or fitting, indicated generally by numeral 4, extending through opening 2 with its face substantially flush with the surface 1. The fixture 4 comprises a short, inverted conical section 5 which, at its upper end is formed with a shoulder 6 and a peripheral flange 7, its lower end terminating in a downwardly extending tubular portion 8 into which is threaded the usual drain pipe 9. Resting on the shoulder 6 within the flange 7 and secured in place by screws 10 is a cover plate 11 having a central opening 12 and, in the area surrounding such opening, a plurality of slot openings 13 through which water drains into the fixture 4 and thence to pipe 9.

15 Housed within the fixture 4 is a stool supporting member 14 formed to slidably receive the lower end of a vertically arranged tube 15 comprising the post or standard of a stool and which at its upper end carries a seat 16. This member 14 may, if desired, form an integral part of the body portion of the drain fixture. It is preferable, however, in employing a standard fixture, not to make any changes or additions other than to the cover plate 11 which, in the illustrated embodiment of the invention, is shown as the part of the fixture carrying the member 14. Plate 11 is therefore made sturdy and of sufficiently heavy stock for the purpose intended and with the parts of member 14 formed integrally therewith in any suitable manner as by welding or brazing.

In this instance the member 14 comprises two tubes forming sleeves 17 and 18 concentrically arranged and in axial alignment with the central opening 12 of plate 11, the tubes being of such diameter throughout their length as to provide an annular channel 19 co-extensive therewith and adapted to slidably receive the wall of tubular post 15. Sleeve 17 at its top is integral with

40 the under face of plate 11. The sleeves 17 and 18 at their lower ends are connected by a closure 20 which forms a bottom for channel 19 and support for the post 15, the top of the inner sleeve 18 having a closure 21 preferably flush with plate 11. Any water entering channel 19 will escape through lateral openings 22 in the outer sleeve 17.

It is preferable that the stool be made collapsible so that, when not in use, it will occupy but a minimum amount of space and in which condition it will be readily accessible, but in an out of the way place such as being suspended from a hook 23, see Fig. 2, against a wall 24 adjacent the shower or bathtub with which the stool is used.

55 While any suitable form of hinge connection

between the post 15 and seat 16 may be employed, that illustrated in the drawing comprises a plate 25 secured by screws 26 to the underside of the seat. At right angles to this plate is a short tubular extension 27 adapted, when the seat is in position for use, to slidably fit within the upper end of post 15 and, with the seat in folded position, to lie transversely on the end of the post. Astride this extension 27, and struck from the plate 25, are arms 28, 28, to each of which at 29 is pivotally connected the upper offset portion of a respective side arm 30 extending upward from a crossbar 31 slidably fitted in diametrically opposed slots 32 in the post 15. Swinging the seat on its pivotal connections from the position shown in Fig. 2, about an angle of 90°, to that shown in Fig. 1, the extension 27 will be aligned with post 15. Then, by exerting downward pressure on the seat there will be a telescoping of the parts 15 and 27 with the seat firmly held against displacement.

From the foregoing, it will be observed that a stool has been provided for a very unique and useful purpose, and that by a simple addition to a drain fitting there has also been provided a distinctly novel and practical means for removably supporting the stool.

What I claim is:

1. A cover plate for a drain fixture, said plate having a central opening and drain apertures in the area surrounding said opening, two concentric cylindrical members in axial alignment with said plate opening and of such diameters as to provide an annular channel between them opening at the top into said plate opening, at least the outer one of said cylindrical members being tubular and formed integrally with said plate, and a closure for the bottom of said channel formed integrally with both said cylindrical members, said channel being provided with a discharge opening.

2. A cover plate for a drain fixture, said plate having a central opening and drain apertures in the area surrounding said opening, two concentric cylindrical tubes in axial alignment with said opening and having an annular space between them opening at the top into said plate opening, the outer one of said tubes being attached to said plate, a closure for the top of the inner one of said tubes, and a closure for the bottom of said annular space, such closure forming a connection between said tubes.

3. A drain fixture comprising two members, one including an internally threaded annular portion and an upwardly opening body portion inclined outwardly from said annular portion and the other comprising a perforated cover plate fitted to said body portion, and a projection formed integrally with one of said members and

extending axially through said annular portion, said projection having an annular channel substantially coextensive therewith, said channel opening at the top through said cover plate and being closed at the bottom.

4. A drain fixture in accordance with claim 3 and characterized by said channeled projection being carried by said cover plate.

10 5. A drain fixture in accordance with claim 3 but characterized by said projection comprising two concentric cylindrical tubes spaced apart to provide said annular channel, and by the closure for said channel being a closure for the bottoms of said tubes.

15 6. The combination, with a surface to be drained and having a drain opening, of a fixture seated in said opening, a stool comprising a post extending upward from said fixture and a seat on said post, and post receiving means housed within said fixture for removably supporting said stool.

20 25 7. The combination with a surface to be drained and having a drain opening, of a fixture seated in said opening, a stool comprising a tubular post extending upward axially of said drain fixture and a seat on said post, and stool supporting means housed within said fixture, said means providing an upwardly opening and bottom closed annular channel for slidably receiving said post, said channel having an outlet to the drain.

20 30 8. A combination in accordance with claim 7 but characterized by said drain fixture including two parts, viz., a body portion and a removable perforated cover plate, and by said stool supporting means being formed integrally with said cover plate.

35 40 9. A combination in accordance with claim 7 but characterized by said stool including a hinge connection between said post and said seat, and means on said cover cooperating with said tubular post to lock the seat against displacement when the seat is in position for use.
